UNITED STATES PATENT OFFICE.

SIEGFRIED HELD, OF CHICAGO, ILLINOIS.

OIL BURNER.

Application filed November 13, 1925. Serial No. 68,770.

This invention relates to an oil burner of that type adapted for use in connection with furnaces in dwellings or the like, for steam and hot water systems, but which is susceptible of use in all situations for which it is adaptable.

It is among the objects of this invention to provide a burner that is substantially noiseless; that is economical in the consumption of fuel; in which there is little or no carbonization; that provides a broad heating area; that can readily be adjusted for insertion in a furnace of any character and that is automatically controlled.

With these and other objects in view, which will become more apparent in the following description and disclosures, this invention comprises the novel structure and combinations hereinafter described and more particularly pointed out and defined in the appended claims.

In the accompanying drawings which illustrate a preferred form of this invention and in which similar reference numerals refer to similar features in the different views:

Figure 1 is a side elevation of the device. Figure 2 is a top plan view of the burner device with parts removed and parts shown in section.

Figure 3 is a vertical sectional view through a part of the burner device.

Figure 4 is an enlarged fragmentary top plan view of the control mechanism at the front part of the device.

Figure 5 is an enlarged sectional view taken on line V—V of Figure 4.

Figure 6 is an enlarged sectional view taken on line VI—VI of Figure 4.

Figure 7 is an enlarged top plan view of the radially adjustable hollow arms carrying the burner disks and enclosing fuel chambers.

Figure 8 is an enlarged horizontal and fragmentary sectional view through one of the vapor controlling valves, taken substantially upon the line VIII—VIII of Figure 3.

Figure 9 is an axial sectional view through the pressure regulating valve.

Figure 10 is a sectional view upon the line X—X of Figure 9.

Figure 11 is an enlarged sectional view upon the line XI—XI of Figure 10 with parts omitted.

Figure 12 is a sectional view taken upon the line XII—XII of Figure 5.

Figure 13 is a sectional view through the liquid fuel valve.

Figure 14 is a side elevational view of the valve mechanism shown in Figure 13.

Figure 15 is an end elevational view of the fuel valve shown in Figure 13.

Figure 16 is a sectional view taken on line XVI—XVI of Figure 1.

Figure 17 is a top plan view of a gas burner for use for primarily generating the vapor or gas from the oil.

Figure 18 is a bottom plan view of Figure 17.

Figure 19 is a diagrammatic view of the control system.

As shown on the drawings:

The structure illustrative of this invention comprises means for regulating the pressure of the liquid fuel delivered to the burner; means for vaporizing the fuel; means for superheating the vapor and gasifying the same before it is delivered to the burner; means for regulating the amount of air mixed with the vapor or gas and a control which will automatically reduce the amount of fuel to a negligible quantity when a great deal of heat is not required.

The means for controlling the pressure of the liquid fuel comprises a pressure regulating mechanism denoted as a whole, by the reference numeral 1, in Figures 1, 2, and 9. It is placed in the fuel supply pipe 2.

In referring to Figures 9 to 11, it will be noted that this regulating mechanism comprises a cylindrical body portion 3 having a liquid fuel inlet 4 and an outlet 5. The inlet 4 communicates with a passage 6 in a bridge 7 that extends across the interior of the cylinder 3 and has a pair of plugs 8 and 9 threaded therein from opposite sides. The plug 9 forms a valve seat while the plug 8 closes an inspection aperture. The outlet 5 communicates with a passage 10 formed in an inwardly projecting ledge 11 which has a lower threaded plug 12 forming a valve seat.

The ends of the body portion 3 are enlarged and internally threaded for receiving suitable open-ended caps 13 and apertured disks or rings 14 at the inner ends of the caps. The rings and caps are in separable threaded

connection with the body portion. In the open ends of the caps 13 are threaded cylindrical cup-like members 15 which form sockets for coil springs 16 which respectively 5 press against the outer ends or heads 17^a of bellows diaphragms 17, the inner ends of which rest upon and are secured to the rings 14. The head of each diaphragm is provided with a guide rod 18 that extends 10 through a bearing aperture in the end of the adjacent caps 15.

The head of the diaphragm adjacent the passage 6 of the inlet port, supports a frame comprising an end member 19 having a 15 spherical head 20 retained in a groove 21 in a block 22 attached to the inner side of the head 17^a. A pair of parallel rods 23 attached to the head member 19 extends through suitable bearing apertures in the bridge 7 and connect 20 to a cross head 24 upon which a needle valve 25 is supported that extends into the valve port in the plug 9.

The head 17^a of the lower diaphragm supports a grooved block 26 upon its inner side, 25 to which a valve or metering pin 27 is secured; the pin having a head fitting in the groove of the block. The shank of this valve pin is provided with a pair of grooves 28 and 29 in which fit the heads 30 of leaf spring 31 30 which are attached to the valve plug 12.

The diaphragms are normally adjusted for a predetermined pressure, in the present instance fifteen pounds pressure for the inlet valve 25, and twelve pounds pressure for the 35 shut off valve 27. This adjustment is effected through the rotation of the adjustable caps 15 to vary the strength of the springs 16. The liquid fuel entering through the inlet 4 and passage 6 will pass through the port 40 9 controlled by the conical or needle valve 25 into the space or chamber interior of the body portion 3. This liquid fuel is fed under pressure into this regulating mechanism. If the pressure in said chamber rises above the 45 predetermined value, the diaphragm 17 supporting the valve 25 will be actuated and move the said valve 25 to close the valve port in the plug 9. If the initial pressure drops to twelve pounds, which may be predetermined, the pressure on the diaphragm that 50 holds the outlet valve 27 open will be relieved, allowing the said outlet valve 27 to be closed by the spring 16. Under proper pressure and normal working conditions the valves 25 and 55 27 will both be open for the passage of liquid fuel.

The liquid fuel under a predetermined pressure will pass from the outlet 5 in the regulating valve mechanism through a pipe 32 (Figure 2) which is connected to a pipe 33 leading to a control valve mechanism denoted as a whole by the reference character 34 and which is shown in detail in Figures 13 to 15. In referring to said figures, it will be noted 60 65 that the pipe 33 leads to a strainer chamber 35

in which a strainer 36 is inserted through the outer end of the chamber which is closed by a plug 37. The inner end of the chamber is closed by a threaded plug 38 having a central aperture providing a port 38' for the passage 70 of liquid fuel. The outer end of the passage is of conical formation to receive the conical point of a valve 39 on a rod 40 which is anchored to the head 41 of a bellows diaphragm 42 supported in a closed end sleeve 75 43 which is threaded in a cylindrical opening co-axial with the strainer chamber and communicating therewith. The inner end of said opening is reduced to provide an annular shoulder 44. A ring 45 is clamped between this shoulder and the sleeve to afford a support for the open end of the diaphragm. A spring 46 confined in the closed end of the sleeve 43 acts upon the head of the bellows diaphragm to normally close the valve. 85

An arm 47 extends from the end of the valve casing; a lever 48 is pivoted upon this arm. This lever has an enlarged aperture through which the valve rod 40 extends; the valve rod being provided with a collar 49 90 adjacent the lever. The lower end of the lever slopes outwardly as indicated at 50. Another arm 51 projects from the casing. A rod 52 is journaled in this arm. A cam 53 is secured upon the arm for coaction with 95 the sloping rod 50 of the lever. An arm 54 is secured upon the rod 52 for supporting a trip bucket 55 (Figure 2). The normal weight of the trip bucket will normally hold the valve 39 in open position against the tension of the spring 46. However, when the trip bucket becomes filled with oil it will rotate the cam 53 from under the lever 48 allowing the spring 46 to shift the valve 39 to closed position for shutting off the supply of oil. The strainer chamber 35 is provided with a drain outlet 56 which is normally closed by a rotatable valve 57. 100

An L shaped passage 58 extends from the cylindrical chamber between the filter chamber and the bellows diaphragm 42, and communicates with a cylindrical chamber 59 in the upper part of the valve casing. A rotary valve 60 operates in this cylindrical chamber. This rotary valve has a transverse 110 passage 61 which is the normal fuel feeding passage and a smaller passage 62 preferably at right angles to the passage 61. The valve 60 may be rotated to bring either the duct 61 or 62 in communication with the L shaped 115 passage 58. A central passage 63 in the rotary valve extends from the passages 61 and 62 and communicates through passage 64 with an outlet chamber 65 from which the oil escapes through a pipe 66. This chamber is provided with an inspection opening closed by a plug 65^a. 120

The outer end of the valve chamber 59 is closed by a plug 67 which has a threaded connection with the valve casing. The rotary 130

valve has a stem 68 extending through said plug which is provided with a common form of stuffing box 69. The outer end of the stem 68 has a transversely extending pin 70 located in a groove 71 of a clutch block 72 in which a shaft 73 is co-axially secured with the stem 68 by means of a set screw 74. This shaft 73 extends into a switch box 75 (Figure 14) to which reference will later be made.

10 On each side of the casing there is a rearwardly extending wing 76 which is best shown in Figure 2, and which is provided with an attaching flange 77 for attachment to the rear end 78 of the burner frame.

15 The liquid oil escapes from the outlet chamber thru the beforementioned pipe 66, Figures 2, 14 and 15, which extends into one of the hollow side rails 79 and emerges therefrom at the rear end where it has a transverse branch 66^a, which connects with a vertical branch 66^b (Figure 1) that in turn is connected to a hollow rib 80 (Figure 18) on the bottom of the gas burner 81 which consists of a hollow cylindrical member having a central hub 82. A continuous passage 83 (Figure 3) extends through the rib 80 and hub 82.

20 A vapor superheater 84 is supported upon the upper end of the hub 82 which projects about the cylindrical chamber, by means of a socket 85 engaging over such hub. While this superheater may be of any design it preferably consists of a cylindrical member provided with a spiral passage 86 as shown more clearly in Figure 16, the walls of which are provided with suitable vertical passages 87 which extend therethrough to provide a thoroughfare for the flames for heating the superheater and the vaporizer therefor.

25 The superheater 84 is provided with a central upwardly projecting hub 88 having a bore 89 which terminates at its bottom in a reduced bore 89^a extending through the upper part of the socket member 85. A pipe 90 is secured in the reduced bore 89^a and extends through the bore 89 and into a vaporizing chamber 91 formed by a metal dome-like member 92 provided with a bottom closure plate 92^a supported upon the hub 88 of the superheater 84. A conical shield or oil spreader 93 is secured upon the upper end of the pipe 90. A pipe 94 is threaded in the hub 88 concentric with the pipe 90. This pipe 94 is larger than the pipe 90 so as to define a passage therebetween for the escape of the vapor, and since it extends upwardly under the shield 93, no liquid fuel is likely to enter the same. The enlarged bore in the hub 88 communicates with the spiral passage 86 in the superheater. Consequently the vaporized fuel in the chamber 91 will escape through the passage between the concentric pipes 90 and 94 and enter the superheater 84 where the vapor will be superheated.

From the superheater the heated vapor enters a pipe 95 and is conveyed to a lower transverse chamber 96 (Figure 8) formed in a hollow transverse member 97 of the frame. The transverse member 97 is provided with a pair of similar outlet ports 98, the structure of one being shown in detail in Figure 8. The transverse member 97 has a pair of bearings 100 in alignment with the respective ports 98. A valve rod 101 is slidably mounted in each bearing. The forward end 75 of each rod has a conical shoulder 102 that fits in a conical seat formed at the entrance to each port, and a forwardly projecting pin 103 that extends through the port and that cleanses the port of soot or the like during 80 the sliding movements of the rod.

The transverse member 97 is integral with the end bearings 104 which support the forward ends of the hollow rods 79. A bar 105 integral with the bearings 104 extends in parallel spaced relation with the transverse member 97. The bar 105 is provided with bearings 106 in alignment with the ports 98. A pipe 107 is secured in one bearing and a pipe 108 is secured in the other bearing. A 90 short tube 109 is slidably mounted in the end of each pipe 107 and 108, and has an operating rod 110 attached thereto. The space between the members 97 and 105 provides an air gap for the mixture of air with the fuel vapors or gas as in an adjustable Bunsen burner. By adjusting the tubes 109, across the air gap, the volume of air mixed with the fuel will be varied.

95 The pipe 107 is connected to a hollow casting 111 which is best shown in Figure 2. This casting is provided with three upwardly extending hollow branches 112, 113 and 114, located at the rear of the burner and which form fuel chambers. The rear end of a hollow arcuate arm 115 (Figure 7) is removably journaled upon the upper end of each of the branches 112 and 114. The middle branch 113 is connected to the gas burner mechanism 81 as best shown in Figure 3.

100 The mechanism 81 consists of a cylindrical casting or the like having a circumferential gas chamber 116 the ends of which terminate adjacent the passage 117 (Figure 17) that leads from the branch 113 to a central chamber 118. The top of the circumferential chamber 116 is provided with suitable apertures 119 for the escape of gas during combustion. A gas pipe 120 which may be connected with the city main and provided with a valve 120^a extends into the gas chamber 116 as shown in dotted lines in Figure 17. The top of the central chamber 118 is provided with a series of perforated plugs 121 for the escape of the oil vapors during combustion.

115 120 125 The aforementioned arms 115 in their normal positions concentrically embrace the cylindrical member 81. In the top of these

arms are inserted suitable apertured plugs 121 for the escape of oil vapors during combustion. These arms are so journalled upon the branches 112 and 114 that they may be 5 swung outwardly as shown in dotted lines in Figure 7 and removed therefrom when desired.

The aforementioned pipe 108 (Figure 2) is connected to a hollow casting 122 having a 10 pair of upwardly extending hollow branches 123. A hollow arcuate arm 124 (Figures 3 and 7) is journalled at its rear end upon each of the branches 123. These arms enclose fuel 15 chambers and the top of each arm has a plurality of apertured plugs 121 inserted therein for the escape of the vapor during combustion. These arms may be readily removed and subsequently replaced to facilitate installation and they may be substituted by 20 other arms for a larger or smaller furnace, to conveniently adapt the device for a larger variation of conditions to be encountered without excessive cost. These arcuate arms 124 normally lie closely adjacent the arcuate 25 arms 115, but they are adapted to be swung outwardly as shown in dotted lines in Figure 7, so that the flame may be carried nearer to the outer wall. The inner arms 115 may be likewise adjusted. The arms may be temporarily 30 removed where the burner is to be inserted into a furnace.

The vaporizer 92, the superheater 84, and the cylindrical member 81 that provides the 35 gas burner, are removable as a unit. In referring to Figure 18, it will be noted that the bottom of the cylindrical member has a plurality of sockets 125 that fit over supports 126 which rise from the bridge 127 of U-shaped brackets 128 supported in a drip pan 129 which in turn is supported upon suitable legs 40 or pedestals 130. The forward end of this drip pan is provided with an outlet port 131, (Fig. 3) from which a pipe 132 (Figure 1) extends to the aforesaid trip bucket 55.

45 The function of this trip bucket is old and well known. If the burner should unintentionally become extinguished the oil will overflow into the drip pan and run into the trip bucket which when full will release the lever 48 by effect of gravity and allow the 50 spring 46 to close the valve 39 in the oil pipe line.

The beforementioned valve rods 101 are jointed to rods 133 which extend through the 55 front end 78 of the burner (Figures 2 and 4); cross-heads 134 are secured upon these rods adjacent the outer side of the end members 78; each cross head has a pair of rollers 135, one at each end, which are adapted to roll 60 against cam members 136 secured upon the end frame member 78. Each cam member has a pair of diametrically opposite elevations 137 with intermediate valleys or dwells. When the rods 133 are rotated to bring the

rollers upon these elevations the valve rods 65 133 will be retracted for opening the valves 98. Coil springs 138 surround the rods 133 between the end frame member 78 and suitable shoulders 139 on the rods. When the valves 98 are opened, these springs are compressed. When the cross-heads ride off the elevations 137 of the cams the springs will automatically shift the valve rods to close the valve ports. 70

The valve rod on the left as viewed in Figures 4 and 5 is adapted to be manually controlled, while the one on the right is adapted to be automatically controlled. To this end a spur gear 140 is slidably splined upon the outer end of the right hand rod 133. The gear 140 meshes with a small pinion 141 (Figures 5 and 12) secured upon a stub shaft 142 which is journalled in a bearing 143 attached to a plate member 144 supported in spaced relation to the end member 78. A worm gear 145 is secured upon the inner end of the stub shaft 142 and meshes with a worm 146 upon a motor shaft 147, the motor 148 of which being suitably supported on the end member 78. 75 80 85 90

A frictional retarder or brake 149 coacts with the motor shaft to prevent over-running. This frictional retarder comprises a head with a concave recess in which a spring 150 is secured, and a rod 151 extending from said member which is slidably mounted in a bearing 152 adjustably threaded in the end member 78 and supported by a nut 153. A spring 154 between the bearing and head of the retarder serves to yieldingly press the same against the motor shaft. By adjusting the bearing 152, the tension of the spring can obviously be varied. 95 100 105

A spur gear 155 is secured upon the aforementioned shaft 73 and meshes with the spur gear 140. Upon the shaft 73 within the switch box 75 there is a movable switch member 156 (Figure 19) adapted to bridge the terminals 157 and 158 or the terminals 159 and 160 within the box. The terminal 157 is connected with the terminal 160 which in turn is connected by a wire 161 with a post 162 of a switch board 163. The terminal 158 is connected to a post 164 of said switch by a conductor 165 while the terminal 159 is connected by a conductor 165 with the terminal 166 of said switch. 110 115 120

A source of electrical energy is connected to the posts 167 and 168 of said board. The motor 148 is connected by the conductors 169 and 170 to the posts 162 and 167 of the board. 120

A thermostat 171 which is usually in the room or at the point of delivered heat is connected to the switch board 163. The high temperature side 172 of the thermostat is connected to the post 166, while the low temperature side 173 thereof is connected to the post 164. The movable thermostatic element 174 is connected to the post 168. A service 125

switch 175 may be placed in any suitable part of the circuit. It is shown between the switch board and source of current.

The operation is as follows:

- 5 In the drawings certain valves are shown closed, the device being out of operation. It will accordingly be assumed that the thermostatic element 174 is on the low temperature side. Now, to start the burner, the city gas is 10 first turned on and ignited for heating the superheater and vaporizer. When they have been sufficiently heated, the service switch 175 may be closed, the motor circuit will then be completed through the low temperature 15 side of the thermostat, as can readily be ascertained from Figure 19. The manual valve 102 is opened and fuel is admitted to the inner burner 81 and the burners 121 in arms 115. Now when more heat is required, the motor 20 will then start and it will rotate the right hand shaft 133 to ride the rollers 135 upon the elevations of the cam 136 at the same time withdrawing the valve rod 101 for opening its port 98; the rod 133 sliding through the 25 gear 140. The motor will also rotate the shaft 73 for rotating the rotary valve 60 for alining the larger port 61 with the passage 58. When this has been accomplished, the switch blade 156 on shaft 73 will have rotated out of 30 contact with the posts 157 and 158 whereby the circuit will be broken and the frictional retarder will cause the motor promptly to stop. If the oil supply line 2 is open and oil is being pumped into the supply system, the oil 35 will flow into the regulating valve which maintains the oil between 12 and 15 pounds pressure. The oil will then flow through the strainer chamber and rotary valve 60 to the vaporizer 92 where the liquid fuel is turned 40 into vapor or gas, which escapes thru the passage between the pipes 90 and 94 to the superheater 84. The heated vapor or gas leaves the superheater through the pipe 95, from which it enters the chamber 96 in the transverse 45 member 97; the vapor or gas passes through the valve parts 98 and crosses the air gap when it is mixed with air and enters the pipes 107 and 108, the former of which conveys the vapor or gas to the fuel chambers 50 in the inner arcuate arms 115 and the chamber 118, in the cylindrical member 81, while the latter conveys the vapor or gas to the fuel chambers in the outer arcuated arms 124. The vapor or gas is ignited from the gas burner 55 which is supplied by the city main. As soon as the oil vapor or gas is ignited the city gas may be cut off.

If the zone in which the heat is delivered becomes too hot, the movable thermostatic element 174 will connect with the high temperature side of the thermostat for completing the circuit through the motor which will operate and rotate the valve 60 for bringing the small passage 62 in alinement with the 65 passage 58 for feeding a smaller amount of

oil; the right hand rod 133 will be rotated to remove the rollers 135 from the elevations 137 of the cam 136 whereby the spring 138 will shift the right-hand valve rod 101 for closing its port 98. The small amount of 70 oil delivered through the port 62 will go through the vaporizer and superheater and be consumed in the inner arms 115 which produces heat and which ignites the fuel in the other burners. As the motor rotates, the 75 switch blade 156 will of course be rotated 90° to bridge the contacts 157 and 158 when the motor circuit will be opened again. When the temperature has been sufficiently lowered to shift the thermostatic element 174 80 to the low temperature side, the motor will be started again for opening the valve once more and so on. As previously explained; the small amount of combustion maintained by the inner arms 115 will serve to ignite 85 the vapor or gas when the system starts up again.

I am aware that many changes may be made and numerous details of construction may be varied through a wide range without departing from the principles of this invention, and I therefore do not purpose limiting the patent granted hereon, otherwise than necessitated by the prior art.

I claim as my invention:

1. In an apparatus of the class described, a control valve for receiving liquid fuel, means for vaporizing said fuel, a pair of fuel chambers communicating with said vaporizing means, a valve for controlling 100 each chamber, and temperature-responsive means for closing one of said valves and for operating said control valve for reducing the flow of fuel through the other valve.

2. In an oil burner, the combination with 105 a pair of fuel burner chambers, common means for supplying fuel to said chambers, and temperature-responsive means for shutting off the supply to one chamber and for reducing the supply to the other chamber.

3. In an oil burner, a cylindrical member 110 forming a fuel burner chamber and provided with an apertured burner top, a passaged superheater having a spiral fuel passage therein supported above said burner chamber, a vaporizer supported above said superheater, concentric conduit means forming a communication between said vaporizer and the spiral passage of said superheater and means for conducting superheated fuel vapor 115 from said superheater to said burner chamber.

4. In an oil burner, the combination with 120 a plurality of separate oil burner chambers, of a valve for each of said chambers, a common oil supply line leading to said valves, a control valve in said supply line and means for automatically closing one of said valves and reducing the flow of oil through said control valve to the other valve.

95

105

110

115

120

125

130

5. In an oil burner, the combination with a plurality of separate oil burner chambers, of a valve for each of said chambers, a common oil supply line leading to said valves, a control valve in said supply line and thermostatically controlled means for automatically closing one of said valves and reducing the flow of oil through said control valve to the other valve.
- 10 6. In an oil burner, the combination with two fuel burner chambers having a common fuel supply line, of a pair of valves in said supply line, one for each chamber and automatically operable mechanisms for closing one valve and reducing the flow of fuel through the other valve.
- 15 7. In an oil burner, the combination with two fuel burner chambers having a common fuel supply line, of a pair of valves in said supply line, one for each chamber, a manu-
- ally operable control for one valve, an automatic control for the second valve and means operated by said automatic control for reducing the flow of fuel through said manually operable valve.
- 20 8. In an oil burner, the combination with two fuel burner chambers having a common fuel supply line, of a pair of valves in said supply line, one for each chamber, a manu-
- ally operable control for one valve, an automatic control for the second valve and a rotary valve in said common supply line having ports of different size, operated by said automatic control which in turn is thermostatically operated to reduce the flow of fuel through said manually operable valve when the automatically operated valve is closed.

In testimony whereof I have hereunto subscribed my name.

SIEGFRIED HELD.
